 Ohio, a corporation of Ohio

Application January 31, 1950, Serial No. 141,511

7 Claims. (Cl. 271—62)

1

This invention relates to improvement in pile elevators, that is to say a mechanism for intermittently raising a pile of sheets to maintain the level of the pile at a predetermined height in order that sheet feeding mechanism may function properly. The mechanism is illustrated as applied to a sheet collator having a series of hoppers from which sheets are fed to a collecting conveyor.

One of the objects of the invention is the provision of a pile elevator which shall be of simple design and low cost and adapted particularly although not exclusively for use in sheet collators.

Another object is the provision of an elevator for sheets in a hopper that is inclined somewhat away from the vertical toward the forward face of the hopper, having operating mechanism of such nature that it affords more or less continuous agitation tending to jog the sheets of the pile forward against the pile guides.

Other objects and features of novelty will appear as I proceed with the description of that embodiment of the invention which, for the purposes of the present application, I have illustrated in the accompanying drawings, in which

Fig. 1 is an endwise elevational view with the end casing of the machine removed to better illustrate the invention.

Fig. 2 is a side view taken substantially along the line 2—2 of Fig. 1.

Figs. 3 and 4 are fragmental detail elevational and plan views illustrating yieldable fingers bearing upon the front top corners of the pile for assisting in the separation of sheets.

Fig. 5 is a detail sectional view on a larger scale, the view being taken substantially on the line 5—5 of Fig. 1, and

Fig. 6 is a detail sectional view taken substantially on the line 6—6 of Fig. 2.

Fig. 7 is a fragmental side elevational view with parts in section of a block 58 and associated parts on a larger scale.

Fig. 8 is a detail elevational view looking in the direction indicated by line 8—8 of Fig. 7, and

Fig. 9 is a fragmental detail view looking in the direction of line 9—9 of Fig. 7.

The frame of the machine embodies a base 10 and end walls 11, and preferably has one or more intermediate walls parallel to the end walls and not shown in the drawings. The intermediate and end walls are joined by longitudinal members which may include a pair of braces 12 near the bottom of the machine, solid bars 13 and 14 and a tubular bar 15.

Shafts 16 and 17 extend the full length of the machine, having bearings in the end walls 11 and preferably also in the intermediate walls. Shaft 16 turns continuously, one revolution for each machine cycle. In every cycle a sheet is fed from the top of each pile of sheets onto a tray 18 which runs lengthwise through the machine, this tray having a longitudinal slot 19 through which a

2

series of pins 20 extend. These pins, which are spaced apart the same distance as the hoppers, are mounted on an endless conveyor chain 21 which operates intermittently, being advanced after each feeding operation a distance equal to the distance between consecutive pins, whereby the sheets from the various hoppers are collected in stacks and delivered at the end of the upper run of chain travel.

10 Mounted on the base of the machine there is an electric motor 21 which drives a speed reducer 22 from which are driven two shafts 23 and 24. Shaft 24 carries a sprocket wheel which drives a chain 25 that extends upwardly and around a sprocket wheel on a short shaft 26 which is concentric with the sprocket wheel for conveyor chain 21. Interposed between shaft 26 and the sprocket wheel for chain 21 there is a one revolution clutch which is automatically actuated once 20 during each machine cycle for advancing the chain as previously described. Shaft 23 turns once for each machine cycle and carries a cam disk 27. Shaft 16 is driven from shaft 23 on a one to one ratio.

25 A plurality of upwardly extending arms 28 are clamped to the oscillating shaft 17. In the free ends of these arms there is journaled a hollow shaft 29 which extends the length of the machine. This hollow shaft is closed at its ends and is 30 subjected to vacuum by means of a flexible hose 30 which communicates with the shaft near the middle thereof. The lower end of the hose connects with a vacuum pump, not herein shown. Shaft 29 opposite each hopper carries a pair of 35 sucker supporting arms 31 having sucker heads 32 at their outer extremities which are connected with the hollow shaft 29 by flexible conductors 33. In order to permit adjustment of the degree of suction for the different paper piles 40 individually there is provided opposite each hopper a fitting 34 to which the conductors 33 are connected, the fitting carrying a needle valve 35.

The large disk 27 keyed to shaft 23 carries two face cams, not shown, which operate linkage by 45 means of which shaft 17 is oscillated to move hollow shaft 29 from the full line position of Fig. 1 to the dotted line position thereof and back again in each machine cycle. During this cycle hollow shaft 29 is oscillated in the arms 50 28 to raise and lower the sucker heads at the proper points in the cycle. The mechanism for accomplishing these movements per se forms no part of the present invention, and accordingly is not illustrated in detail. The pile elevating 55 mechanism for maintaining the top of the pile at the proper level for cooperation with the sucker heads during operation of the feeder will now be described.

The hopper for each pile comprises upper and 60 lower side rails 37 and 38 which have holes to receive longitudinal bars 14 and 15 and are clamped to those bars by screws 39 and 40 ex-

tending across slots formed in the rails between the ends thereof and the holes for bars 14 and 15. These rails 37 and 38 support by means of suitable fastenings upright corner members 41 of the hopper which constitute guides for the front and side edges of the pile. At the rear of the pile the rails 37 support short uprights 42 which are adjustable forwardly and backwardly to a limited extent. In these uprights there is mounted a rod 43 which supports a rear guide 44 that may be adjusted to a selected position along the length of the rod.

The tubular member 15 acts as an air blast manifold, being closed at one end and at the other end being connected by a conductor 45 with the outlet side of the air pump. At a point opposite each hopper a nipple 46 connects tubular member 15 with a hose 47 which extends to the lower end of a pipe 48 that is supported in a block 49 which is adjustable along the tubular member 15. At its upper end pipe 48 is provided with a slot 50 through which air is blown against the sheets at the top of the pile for sheet separating purposes.

52 is a plate that is movable up and down between and behind the corner members 41 of the hopper. Upon it may be placed a sheet 53 of heavy cardboard of the same size as the sheets S of the pile. This plate is securely mounted on the upper end of a rack 54 which is movable up and down in guides 55 and 56 that are carried by a plate 57 which is bolted to one edge of a heavy plate or block 58. These blocks are provided with holes to receive the brace bar 13. Each block is slotted as at 59 and a screw 60 is mounted in the block and extends transversely of the slot, being threaded at 61 in the block in order to clamp the latter firmly upon the brace bar. All of the blocks therefore are carried by bar 13 and the pile supporting racks in turn are carried by the individual blocks.

The shaft 16 extends through all of the blocks 58 and has a supplemental bearing in each block. An eccentric 63 is mounted upon and secured to shaft 16 adjacent each block 58 as by means of a set screw 64. Surrounding the eccentric near one end thereof there is a ring 65. The eccentric is free to turn within the ring 65, but in order to hold the two parts against relative movement lengthwise of shaft 16 a set screw 66 projects through the ring into a peripheral groove 67 formed in the eccentric. Welded or otherwise secured to the ring 65 is a pull rod 68 which projects upwardly through an opening 69 in a foot 70 forming part of a feeler bar 71 that is guided for up and down movement by suitably shaped yokes 72 and 73 fastened to rails 38 and 37 respectively. A collar 74 adjustably secured to rod 68 underlies a washer 75 which engages the lower surface of foot 70 and thus transmits upward movement of rod 68 to the feeler bar 71. The upper end of rod 68 carries an adjustable nut 76 which backs a washer that bears against the upper end of a coil spring 77 surrounding the rod, the lower end of the spring bearing against a flat face on the upper side of a slidabile washer 78 with a convex lower surface that engages the foot 70 around the periphery of hole 69. Downward movement of pull rod 68 therefore transmits force to foot 70 through the spring 77, and if the foot is not free to descend the pull is absorbed by the spring.

Each block 58 carries a stub shaft 78 upon which is journaled the hub 79 of an arm 80 which projects over eccentric 63. On this arm there is

a projecting lug 81 which is disposed beneath the head on the lower extremity of a screw 82 which is adjustably threaded in a tapped hole in foot 70 and held in adjusted position by a lock nut 83. The upper end of feeler bar 71 has a horizontal extension 84 which overhangs the pile of sheets S and is adapted to engage the top of the pile when downward force is transmitted to feeler bar 71 by the ring 65.

10 Each time a sheet is fed forward off the pile the feeler bar 71 descends and engages the pile. When the lowered height of the pile permits the feeler bar to descend far enough, screw 82 acting through lug 81 swings arm 80 downward about its pivot 78, the high point of the eccentric being then below shaft 16. If the downward swing of arm 80 is sufficient a pawl 85 pivotally mounted on the free end of the arm travels downwardly far enough to engage the next lower tooth on the toothed side of rack bar 54. As soon as the high point of the eccentric again comes uppermost a follower wheel 86 carried by arm 80 is lifted by the eccentric, thereby acting through pawl 85 to raise the rack a distance equal to the distance between consecutive teeth on the rack. When this occurs the upward movement of the rack causes a second pawl 87 which is pivoted to the block 58 to snap under the next tooth of the rack and support the latter. The upper ends of pawls 85 and 87 are pivotally connected with plungers 88 and 89 which extend through slots in plate 57 and are biased outwardly by springs 90 bearing against the heads of the plungers. The pawls are thus resiliently held in engagement with the toothed side of the rack.

20 In order to assist in the separation of the uppermost sheet of the pile when it is taken by the sucker heads 32 I may mount at the two front corners of the hopper resilient wire fingers 92. When the sucker heads pull the top sheet out from under these fingers the fingers tend to retain the next sheet on the pile and prevent it from adhering to the top sheet. Removable screws 93 projecting through loops on the fingers serve to mount the fingers and readily permit the substitution of fingers of different characteristics in order to improve the sheet separating action and compensate for differences in paper stock.

30 When it becomes necessary to replenish the sheets in a given hopper the operator may push in the plungers 88 and 89, which permits the plate 52 to descend until a stop pin 94 on the rack engages the uppermost guide 55. The plungers 88 and 89 are then released and the pile is built up to the desired height. Then with the eccentric 63 turned to a position diametrically opposite to that illustrated in the drawing the rack 54 may be pushed up by hand to cause the top of the pile to engage the feeler rod extension 84. With all of the hoppers thus filled suction may be turned on in hollow shaft 29 and compressed air turned into tubular member 15, after which motor 21 may be started and the operation of all feeders begun. Directly after the rear edge of the sheet being fed passes forward beyond the extension 84 of the feeler bar that bar is pulled down by the eccentric ring 65. If the stock being fed is light a considerable number of reciprocations of pull rod 68 may result merely in the compression of spring 77 and the depression of pawl 85 a distance insufficient to enable it to snap under the next lower tooth of the rack. In each cycle the eccentric raises the follower 86 slightly however and causes the pawl 85 to push the rack upwardly a distance less than

the spacing of the teeth after which is descends until caught by the pawl 87. A constant slight jogging of the rack therefore takes place, which has a beneficial result in jarring the sheets S forward against the corner members 41 of the hopper to maintain an accurate pile.

As soon as the level of the pile descends sufficiently screw 82 acting through lug 81 on the swinging arm 30 depresses pawl 85 into engagement with the next lower tooth, and the next upward movement of the eccentric functions through follower 86 to raise the pawl 85 and push up the rack, the pawl 87 then snapping into position beneath a lower tooth of the rack and supporting it. The operation continues until the plate 52 has risen nearly to the upper limit of its movement when the machine should be stopped and the pile of sheets replenished.

Having thus described my invention, I claim:

1. In combination a hopper plate for supporting a pile of sheets, a rack operatively connected with said hopper plate and adapted upon endwise travel to move the hopper plate up or down, ratchet teeth on one side of said rack, means for preventing retrograde travel of said rack, a support movable up and down in a direction generally parallel to said rack, a pawl on said support spring-pressed into engagement with the toothed side of said rack, a vertically reciprocable feeler bar the upper end of which on its down stroke is adapted to engage the top of the pile and the lower end of which is adapted to bear upon and depress said support, means for raising said feeler bar once for each cycle of the machine, and means effective during the up-stroke of the feeler bar to move said support upward, whereby a downward movement of the feeler bar of sufficient extent to depress the pawl into engagement with the next lower tooth of the rack results in the raising of the rack during the upward movement of the feeler bar.

2. In combination, a hopper plate for supporting a pile of sheets, a lengthwise movable upstanding rack for supporting said hopper plate, ratchet teeth on one side of said rack, a pawl spring-pressed into engagement with the toothed side of said rack to hold it against downward travel, a pivoted arm swingable through a small arc tangent to the direction of travel of said rack, a pawl on said arm spring-pressed into engagement with the toothed side of said rack, a vertically reciprocable feeler bar the upper end of which on its down stroke is adapted to engage the top of the pile and the lower end of which is adapted to bear upon and depress said swingable arm, means for raising said feeler bar once for each cycle of the machine and means effective during the up-stroke of the feeler bar to swing said arm upward, whereby a downward movement of the feeler bar of sufficient extent to depress said arm supported pawl into engagement with the next lower tooth of the rack results in the raising of the rack during the upward movement of the feeler bar.

3. Pile elevating means as defined in claim 2, comprising endwise movable rods pivotally connected to said pawls and spring pressed to urge the pawls toward rack engaging position, said rods being manually movable to disengage the pawls from the rack and permit downward movement of said rack when the pile of sheets is to be replenished.

4. In combination, a hopper plate for supporting a pile of sheets, a lengthwise movable upstanding rack for supporting said hopper plate,

ratchet teeth on one side of said rack, a pawl spring-pressed into engagement with the toothed side of said rack to hold it against downward travel, a pivoted arm swingable through a small arc tangent to the direction of travel of said rack, a pawl on said arm spring-pressed into engagement with the toothed side of said rack, a feeler bar the upper end of which is adapted to engage the top of the pile and the lower end of which is adapted to depress said swingable arm, an eccentric disposed beneath said arm, means for rotating said eccentric, a ring surrounding said eccentric, a pull rod attached to said ring and connected to said feeler bar through a compression spring, whereby said spring is stressed during each rotation of said eccentric and said arm is depressed sufficiently, when the height of the pile permits, to enable the pawl on the arm to engage the next lower tooth of the rack, said arm carrying a follower adapted to bear on said eccentric whereby said eccentric raises said feeler bar and said arm simultaneously to lift the pile while the feeler bar is rising.

5. Pile elevating means as defined in claim 4, comprising endwise movable rods pivotally connected to said pawls and spring pressed to urge the pawls toward rack engaging position, said rods being manually movable to disengage the pawls from the rack and permit downward movement of said rack when the pile is to be replenished.

6. In combination, a hopper plate for supporting a pile of sheets, a lengthwise movable upstanding rack for supporting said hopper plate, ratchet teeth on one side of said rack, a pair of pawls each spring pressed into engagement with the toothed side of said rack, one of said pawls being mounted on a fixed pivot, a support for the second pawl movable up and down in a direction generally parallel to the said rack, a feeler bar the upper end of which overhangs the top of the pile and the lower end of which is adapted to engage and depress the support for said second pawl, means for moving said feeler bar up and down comprising a yieldable connection adapted to absorb downward thrust after said feeler bar engages the top of the pile, said feeler bar when the height of the pile permits depressing the support for said second pawl through the intermediacy of said yieldable connection far enough to cause the pawl to engage the next lower tooth of the rack, and cam means adapted to raise said movable pawl support during each upward travel of said feeler bar.

7. A pile elevator as defined in claim 6, wherein said cam means is adapted to impart limited raising movement to said movable pawl support whether or not the downward movement of said feeler bar results in the engagement of a new tooth, whereby the pile of sheets on the hopper plate is subjected to jogging action in each machine cycle.
